UNITED STATES PATENT OFFICE

JOHN REID, OF OIL CITY, PENNSYLVANIA

LUBRICATING SYSTEM AND PUMP

Application filed November 22, 1928. Serial No. 321,236.

This invention relates to a lubricating system and a special type of pump for such a system. The lubricating system and pump are particularly adapted for the eccentrics of band wheel or gear powers, or the like.

In my co-pending application, Ser. No. 201,412 Patent No. 1,798,496, March 31, 1931, is shown a power in which the eccentric has an annular trough of substantial size surrounding the eccentric ring for catching the oil flowing from the bearing surfaces of the ring and eccentric. The oil flows to the part of the trough furthest from the center of rotation and collects there in a deep pool from which it can be conveniently pumped. The types of pumps in my aforesaid patent have the disadvantage that the suction duct is so long that it impedes the efficient operation of the pump when the oil becomes thick in cool weather.

According to my present invention the pump is designed so that it can be arranged wholly within the annular trough and substantially submerged in the oil, so that the valves and plunger are continuously immersed in oil and the suction duct can be made very short.

My new pump is furthermore designed so that the plunger is positively actuated in both directions and does not rely on a spring for returning it. The pump is preferably arranged with its plunger tangent to the circular course which it travels with the eccentric so that centrifugal force does not impede the flow of oil on the suction side.

I further provide novel means for actuating the pump and for lubricating the pump actuating parts.

An embodiment of my invention is shown by way of example in the accompanying drawings,

Fig. 1 showing my pump as applied to the eccentric and eccentric ring of a power,

Fig. 2 being a top plan view of the pump,

Fig. 3 being part sectional view of the pump shown in Fig. 2 taken along line 3-3,

Fig. 4 being a sectional view through line 4-4 of Fig. 2,

Fig. 5 being a sectional view through line 5-5 of Fig. 2,

Fig. 6 being a sectional view through line 6-6 of Fig. 2.

Coming now to a description of my invention, 13 represents an eccentric and 14 an eccentric ring. The bearing surfaces 15 formed between the eccentric 13 and the eccentric ring 14 are supplied with oil in known manner. A lip 12 on eccentric 13 forms an annular trough. As the eccentric 13 whirls around the oil from bearing surfaces 15 is thrown out by centrifugal force against lip 12 and is led to that point which is furthest removed from the center of rotation. Here reservoir 11 is located and collects the oil. A pump 10 is placed in reservoir 11.

A turned-in portion 49 on lip 12 forms a labyrinth 50 with eccentric ring 14. This construction of the lip prevents the oil from escaping over its edge and also prevents dirt and dust from entering the oil chamber.

The pump unit indicated in general as 10 comprises a base 16, two vertical supports 17 mounted on the base 16, a two arm rock lever 18 rockably mounted on and between supports 17 by means of pin 19 to which lever 18 is secured by set screw 20, and an arm 21 depending from rock lever 18 and engaging a slotted crosshead 22 in the outer end of plunger 23. Pump 10 is so arranged in reservoir 11 that its plunger 23 is substantially in a position tangent to the circular path which it travels with eccentric 13.

Because of the fact that both ends of the plunger 23 are immersed in oil, the efficiency of the pump is very high.

Cotters 24 serve to retain pin 19 in pockets 25 of supports 17. Pins 26 of rollers 27 arranged in the forked ends 28 of lever 18 are secured in pockets 29 of lever 18 by means of cotters 30.

When eccentric 13 is moved relative to eccentric ring 14, the rollers 27 of lever 18 will abut against cam 31 arranged on ring 14 in any desired number, and plunger 23 will be forced into and out of chamber 32 by the double rocking of lever 18, 21.

The level of the oil in reservoir 11 will normally be over the inlet port 34 so that the oil will flow down conduit 35, across conduit 36, and up through check valve 37, enter-

ing chamber 32 by way of conduit 38 leading from check valve 37. When plunger 23 moves inwardly the oil is forced up through check valve 39 arranged directly over chamber 32 at its inner end, across through a groove 40 formed in cap 41 secured to casing 42 of the pump, down through conduit 43 and out through pipe 44 which leads to a collecting sump (not shown). Bolts 45 serve to secure cap 41 to casing 42.

A pipe 46 is connected to pipe 44 and leads a part of the oil coming from pump 10 to an aperture 47 in eccentric 13. When a bore 48 formed in eccentric ring 14 registers, during the course of rotation of eccentric 13, with aperture 47, the oil will spurt through bore 48 and come out a little above the pump and a little towards the center of rotation of eccentric 13, so that the rollers 27 will be in the path of the oil as it is thrown outwardly by centrifugal forces. The arrangement is such that the rollers 27 will be lubricated from bore 48 at the time they come in contact with cam 31.

It is to be understood that various modifications and changes may be made in the embodiment herein described without departing from the scope of my invention as set forth in the appended claims.

Having thus described my invention,

What I claim is:—

1. In a driving mechanism, the combination of a rotatable eccentric, an eccentric ring therefor, an annular lip extending outwardly and upwardly from said eccentric and forming an annular trough adapted to collect oil flowing from the bearing surfaces of said eccentric and ring, and an oil pump arranged wholly within said trough at the point furthest removed from the center of rotation of said eccentric, whereby said pump may be substantially submerged in the oil collected at said point in said trough.

2. In a driving mechanism, the combination of a rotatable eccentric, an eccentric ring therefor, an annular lip extending outwardly and upwardly from said eccentric and forming an annular trough, an oil collecting reservoir in said trough located at the point furthest removed from the center of rotation of said eccentric, a cam on said eccentric ring, a pump in said reservoir comprising a plunger having a slotted crosshead, a rock lever adapted to be rocked by said cam, and an arm rigidly connected to said lever and cooperating with the slotted crosshead of said plunger.

3. In a driving mechanism, the combination of a rotatable eccentric, an eccentric ring therefor, an annular lip extending outwardly and upwardly from said eccentric and forming an annular trough adapted to collect oil flowing from the bearing surfaces of said eccentric and ring, and a reciprocating pump so arranged within said trough at

the point furthest removed from the center of rotation of said eccentric that the axis of its plunger is tangent to the circular course which it travels with said eccentric.

4. In a driving mechanism, an eccentric, an eccentric ring therefor, a trough on said eccentric surrounding said ring and adapted to catch oil flowing from the bearing surfaces of said eccentric and ring, an oil pump fixed in said trough at the point furthest removed from the center of rotation of said eccentric, a cam on said ring, actuating means for said pump engaging said cam, and an oil conduit leading from said pump through said eccentric and ring to said cam, the continuity of said conduit being controlled by the relative movement of said eccentric and ring.

5. In a lubricating mechanism a narrow chamber, means for passing oil into said chamber, a pump within said chamber, said pump comprising a base, a cylinder arranged on said base, a plunger adapted to be reciprocated in said cylinder and having a crosshead, two supports arranged on said base and at opposite sides of said crosshead, a rock lever mounted on and between said supports and adapted to be rocked around an axis at right angles to the axis of said plunger, an arm rigidly connected to said rock lever at one end and cooperating at its other end with the said crosshead.

6. In a driving mechanism, an inner rotatable ring, a bearing surface thereon, an outer non-rotatable ring on said bearing surface, a trough surrounding said bearing surface to catch oil flowing from said bearing surface, a pump in said trough, a conduit attached to said pump, said pump removing the oil from said trough through said conduit.

The foregoing specification signed at Oil City, Pennsylvania, this 7th day of November, 1928.

JOHN REID.
